UNITED STATES PATENT OFFICE.

DAVIS BARNARD, OF LOS ANGELES, CALIFORNIA, ASSIGNOR TO THE BARNARD LIGHT AND HEAT COMPANY, OF LOS ANGELES, CALIFORNIA, A CORPORATION OF CALIFORNIA.

ACETYLENE-GAS-BURNER CLEANER.

No. 888,777.

Specification of Letters Patent.

Patented May 26, 1908.

Application filed April 15, 1907. Serial No. 368,447.

To all whom it may concern:

Be it known that I, DAVIS BARNARD, a citizen of the United States, residing at Los Angeles, in the county of Los Angeles and

5 State of California, have invented a new and useful Acetylene - Gas - Burner Cleaner, of which the following is a specification.

In the use of acetylene burners, it is found necessary to frequently clean the same, the outlets of the burners being so very small that any slight obstruction will greatly diminish the light and will deflect the flame, thereby causing incomplete combustion and imperfect light; consequently, it is found 10 necessary to provide some means for conveniently cleaning the same. Such means have heretofore been provided by fastening a wire to some sort of holder. Such wires are necessarily very small and liable to be 15 broken. It is further necessary to provide a protection for the wire, and such protection has heretofore been afforded by means of a cap screwed to the end of the handle to house the wire when not in use. Such cap 20 is liable to loss for the reason that it is not in use while the cleaner is in use, and the person using the cleaner is apt to lay the cap aside while using the cleaner, and through 25 inadvertence or otherwise, fail to return it to its place. In case the wire becomes broken 30 from such handle, the instrument is of no further use for the purpose for which it is designed.

It is one of the objects of this invention to 35 provide an acetylene-gas-burner cleaning device which is free from all of the objections heretofore noted, provision being made therein for putting the wire-protecting device into use as a necessary part of the instrument while it is being used for cleaning 40 the light, and provision also being made whereby when one wire is broken from the handle another wire is immediately accessible for use; a large number of wires being 45 stored in the instrument for successive use as the wires from time to time become broken.

Another object is to so construct the device that the case will be detachably held in place by a simple contrivance adding nothing to the cost of the device; to so construct the appliance that each wire may be, in proper succession, bent away from its follows into position for use; and to so con-

struct the device that it is transformable in the easiest and most convenient manner 55 from its adjustment for use as a cleaner to adjustment for carrying in the pocket.

Other objects and advantages of this invention may appear from the subjoined detailed description.

The invention may be applied in different forms, and in the accompanying drawings I shall show the invention in that form I at present deem most desirable.

The accompanying drawings illustrate the 65 invention.

Figure 1 is a view of the appliance folded for storage when not in use. Dotted lines indicate the wires in closed position. Fig. 2 is a view of the appliance with the case removed and one cleaning wire bent over and ready to be inserted into the case. Dotted lines indicate a further position of the case just before the wire and its handle are inserted thereinto. Fig. 3 is an end view of 70 the handle and wires in the position shown in Fig. 2, the same being viewed from the left of the figure, omitting the case. Fig. 4 is a longitudinal, sectional view of the cleaner 75 ready for use. Dotted lines indicate a position into which the cleaning wire may be bent for cleaning bicycle lamps or other lamp-burners difficult of access. Fig. 5 is a plan view of the wire-holder or inner handle before the parts are assembled. Fig. 6 is a longitudinal, sectional view of the holder-body 80 and its bundle of wires, said wires being secured therein aslant instead of being bent as shown in Fig. 2.

1 designates a hollow inner body or chambered holder member provided in one side with an opening 2 and at one end with a longitudinal groove 3. 4 designates wires fastened in said hollow body and accessible through the opening 2 and adapted respectively to be bent over and brought into the groove 3, and to then extend endwise beyond the end of the hollow body 1. Said hollow body may be formed of a section of tube milled out between its ends to form the 90 opening 2, and preferably the end of the opening adjacent the slot 3 will be further shaped into an acute angle 5 from the apex of which the groove 3 extends to the end of the body 1; the purpose of this being to guide each 95 wire into the groove whenever such wire is 100 105

bent over to extend from the end of the body for cleaning purposes. The wires 4 are necessarily of very small diameter, and a large number,—say for example fifty,—may readily be inclosed in one-half the space of a tube of about one-eighth inch internal diameter, ordinarily called three-sixteenths inch tube; and I prefer at present to place the bundle of wires diametrically as far as possible from the grooved side 3, so that there will be as long a bend of the wires as practicable when the same are bent over individually into the groove, the purpose being to give as long life as possible to each wire allowing the same to be bent into and out of operative position a large number of times.

In practical manufacture, the bundle of wires may be placed in appropriate position in the body with the ends of one end of the bundle housed within the grooved end of the hollow body, and there the same may be secured by means of solder 6, or by any other suitable means which may suggest itself to the skilled mechanic.

7 designates a sheath, shell or case adapted to fit upon the body 1 when the wires are brought within the contour of such body. Said sheath serves a double purpose; namely, first that of confining the bundle of wires within the body, and protecting the same from breakage or bending and from wearing the pocket, and from becoming covered with dust or dirt; and second, for holding a single wire in cleaning position when the same has been brought into the groove 3. The sheath 7 serves a further purpose in that it can be used to bring the wire over into the groove after the wire has been started in its separation from the bundle of wires. This is indicated by the slotted positions of parts in Fig. 2.

By reference to Fig. 4 it will be seen that when the sheath is in place on the body 1, it firmly holds the cleaning wire in position for use, the solid and dotted lines by which said cleaning wire is represented, indicate different positions in which the wire may extend from the handle for the purpose of cleaning different forms of burners, or burners in different positions.

By reference to Figs. 2, 3 and 6, it will be seen that the bundle of wires 4 may have a permanent outward tension, thus serving as spring means to retain the holder-body 1 in the sheath or case 7. This tension of the wires may be given thereto by upsetting the same forcibly either before or after the bundle has been secured in the holder-body 1; or the wires may be set aslant in the holder-body, and there soldered as indicated in Fig. 6.

In order to form a convenient closure for the end of the holder-body opposite that provided with the groove, a plug 8 provided with a rounded head 9 may be wedged firmly

into the end of the tubular holder 1. The stem of the plug is preferably slightly tapered, and the plug firmly driven home, thus in a cheap and simple manner forming a closure and a rounded end for the handle of the device. The head 9 projects sufficiently to afford a solid stop against which the sheath 7 comes to rest when fully in place. The head further projects sufficiently to form a slight catch beyond the walls of the sheath 7, so that the fingers may readily grasp the same to withdraw the holder from the sheath.

The appliances will be placed on the market with all the wires inclosed within the sheath. The user may gain access to the wires by simply withdrawing the sheath, and then by uplifting the end of one of the wires he may catch it with the sheath and bring it over into the groove 3, the oblique walls of the angular portion 5 of the opening 2 serving to guide the wire directly into the end of the groove. Then by simply advancing the sheath over the protruding wire and the grooved end of the holder, the wire is firmly brought down into the groove and there held until the sheath has been brought home against the head 9 of the holder. Thereupon, the separated wire indicated by 4' will be left protruding from the end of the cleaner ready for use, and it may be bent to any position desired. When the user desires to again restore the appliance to his pocket, he will simply remove the sheath 7 from the holder-body and protruding wire, and will then bring the end of the holder-body into the sheath, allowing the protruding wire 4' to be outside of the sheath. Then by pushing the sheath from the holder-body, the protruding wire will be brought back into the inside of the sheath along with the bundle of wires, and thereupon the bundle of wires will be compressed and the tension thereof against the sheath will serve to hold the sheath in place.

What I claim is:—

1. A holder provided with a side opening and a bundle of wires inside said holder fastened together and free at one end.
2. A holder provided with a side opening, a bundle of wires fastened inside said holder and free at one end, and means for covering said opening.
3. A holder provided with a side opening and a bundle of wires fastened inside said holder and free at one end, and a sheath for said holder.
4. A holder provided with a side opening, a bundle of wires fastened inside said holder and free at one end, a groove being formed in one end of the holder to receive the wires separately, and a sheath to cover said opening and groove.
5. A hollow holder provided with an opening in one side, a bundle of wires fastened at one end inside one end of the holder, a plug

in the other end of the holder provided with a projecting head, and a sheath for the holder.

6. A hollow holder having an opening, at one side, a bundle of wires fastened by one end in one end of the holder, the other end of said bundle being free and adapted to be separately bent out of said opening into position for use, a sheath for said holder, and a plug in the other end of the holder provided with a head that projects beyond the sheath when the same is on the holder.

7. A holder provided with a chamber and a groove at one end, a wire in the chamber adapted to be bent into the groove, and a sheath to inclose the wire when in the chamber, and to also inclose a portion of the wire when in the groove.

8. A chambered holder provided with a side opening, a bundle of spring wires fastened by one end in one end of the holder, and normally projecting aslant from the holder, and a sheath to normally hold the wires in the holder and to be held on the sheath by engagement of the bundle.

9. A tube provided with an opening in one side, a bundle of wires in the tube free at one end and a plug of solder filling one end of the tube and embedding the ends of the wires at one end of the bundle.

10. A tubular holder having an opening in one side, a bundle of wires having one end free and the other end fastened in the holder at one end thereof and at the side of the holder opposite said opening, said holder having a groove extending from said opening to

the end of the holder to receive the wires separately, and means for holding the wires separately and successively in the groove.

11. A holder provided with an opening in one side and a groove at one end communicating with said opening, said opening terminating in an acute angle communicating with said groove, a wire fastened in the holder and adapted to be bent into the groove, and means for holding the wire in the groove.

12. A holder provided with an opening in one side and a groove at one end communicating with said opening, said opening terminating in an acute angle communicating with said groove, a wire fastened in the holder and adapted to be bent into the groove, and a sheath to cover said opening and to hold the wire in the groove.

13. An acetylene gas-burner cleaner comprising a tube having an opening in one side and a groove at one end communicating with said opening, a plug of solder in such end, a sheath for said tube, a bundle of wires embedded in said solder at one end, and free at the other end and adapted to be separately bent into said groove, and a taper plug wedged in the other end of the tube having a head which forms a stop for the sheath and projects beyond the sheath.

In testimony whereof, I have hereunto set my hand at Los Angeles California this 9th day of April 1907.

DAVIS BARNARD.
